ROTARY ENGINE

Earl E. Bowers, Lebanon, and Charles M. Tumey,
Indianapolis, Ind.

Application July 8, 1935, Serial No. 30,236

4 Claims. (Cl. 121—90)

This invention relates to the art of prime movers of either or both the steam or internal combustion types. The primary object of the invention is to provide a power delivering machine of a rotary type whereby the element being operated on by the expanding gases in the nature of a piston may always travel continuously without having to be alternately stopped and started as in the reciprocating type engine. A further important object of the invention is to provide a very simple, efficient, and durable power unit which, particularly when operated by steam, is easily and readily reversible.

A further important object of our invention is to provide a very simple and positive abutment mechanism in combination with a rotor having a piston-like blade or vane thereon traveling past the abutment. A still further important advantage of the invention lies in the fact that it may be accurately balanced so as to eliminate vibration. Many other advantages such as in the use of particular types of abutments, controls and general structure will become apparent to those versed in the art in the following description of our invention made in reference to the accompanying drawings which show the invention in a more or less diagrammatic and elementary form, there being but one impulse given to the rotor on each revolution on this elemental form, it being understood, of course, that the structure may be multiplied to give more than one impulse per revolution.

Referring to the drawings,

Fig. 1 is a vertical longitudinal section through a form of the invention;

Fig. 2, a transverse vertical section on the line 2—2 in Fig. 1,

Fig. 3, a top plan view;

Fig. 4, a transverse vertical section on the line 4—4 in Fig. 1, and

Fig. 5, a diagrammatic representation of the valve and piping controls.

Like characters of reference indicate like parts throughout the various views in the drawings.

We provide a pair of barrels 170 and 171 which are drawn against a central dividing plate 172 by means of the end plates 173 and 174 through bolts 175.

A shaft 176 preferably hollow is revolvably carried centrally through the three plates 173, 172 and 174 by means of suitable bearings herein shown as roller bearings 177 and 178, respectively, in the end plates and a ball bearing 179 in the center plate. Within each barrel 170 and 171 we mount a rotor 180 and 181 respectively in fixed

positions on the shaft 176 by any suitable means such as by a shrinking fit or by keys 224 so that each rotor will be free to revolve within its respective barrel. The rotors are provided with external cylindrical faces spaced inwardly from the interior wall of each barrel so as to leave an annular passageway therearound between the respective plates 173, 172 and 174 to define chambers, here shown as rectangular in cross section.

Preferably the sides of the rotors are provided with some suitable packing means, here shown as rings 182 as a means for sealing between the rotors and their respective side plates. Referring now to the rotor 180, a radial slot 183 is provided through the cylindrical portion, Fig. 1, and we mount a vane 184 therein to have legs 185 and 186 turned inwardly radially along the inner sides of the plates 173 and 172, respectively. The inner end of each of these legs 186 and 185 carries a roller, here shown as a roller bearing 187 on the side of the leg directed toward the adjacent plate. A cam track 188 is provided on each plate 172 and 173 to receive the bearing 187 revolvably therein. The track 188 extends continuously around the shaft 176 in spaced relation therefrom on each plate.

We provide a stationary blade forming the abutment 189 to extend across the annular passageway between the rotor 180 and barrel 170, Fig. 1, so that the abutment 189 may be in sliding contact with the periphery of the rotor. The cam-tracks 188 are so arranged that the vane 184 is maintained in its extended position as indicated in Fig. 1 wherein its outer edge is in sealing contact with the inner side of the barrel 170 as the rotor 180 revolves.

Each of the cam tracks 188 is further arranged to have a portion thereof extending inwardly toward the shaft 176 centering on the radial axis of the abutment 189 so that as the rotor 180 revolves to carry the vane 184 toward the abutment 189, the rollers in following the tracks 188 will be pulled inwardly toward the shaft and thus retract the vane 184 sufficiently within the slot 183 to permit the vane 184 to pass under the abutment 189 and then be returned outwardly into sealing contact with the barrel 170.

In the same manner a vane 190 is carried by the rotor 181 but preferably in diametrical opposite relation to the vane 184 so that the vane 190 will be normally maintained in sealing contact with the wall of the drum 171 but will be retracted by a depression in the cam tracks 188 carrying the rollers 192 of the vane 190 when the vane 190 approaches the stationary abutment 189.

193 carried across the annular passageway between the barrel 171 and its rotor 181. The vane 190 upon passing the abutment 193 is returned again into sealing contact with the wall of the drum. In the form herein shown, we employ steam as the operating medium. A steam supply pipe 194 enters a timing valve member 195. A drum valve 196 is revolvably carried within the valve member 195 to be revolved by the shaft 176 through the connecting shaft 197. The drum valve 196 has a central dividing partition 198. The drum valve is further provided with slots 199 and 200, Fig. 4, circumferentially spaced apart. A slotted passageway 201 is provided circumferentially around the inner side of the valve member 195 for a major part of the circumference. A short cylindrical portion 202 on the upper part of the inner side of the valve member wall 195 blocks off the upper ends of the passageway 201 and also serves as a closure to the slots 199 and 200 when presented theretoward.

The slot 199 provides communication from the groove 201 into the drum valve chamber 203 while the slot 200 provides communication from that groove 201 into the drum chamber 204.

The chamber 203 opens out into an end of the valve member 195 from which leads the pipe 205. The chamber 204 opens from its outer end into a housing 206 across the end of the valve member 195 from which leads the pipe 207. The pipes 205 and 207 lead respectively into four-way valves 208 and 209. A common exhaust line 210 leads from the valves 208 and 209. These valves 208 and 209 are employed as a means for reversing the direction of rotation of the rotors 180 and 181 and thereby the shaft 176.

From one side of the valve 208 is carried a pipe line 211 around to communicate with the annular passageway in the barrel 171, the pipe entering the barrel at a distance around from the upper center line. A pipe line 212 also leads from the valve 208 around to the barrel 171 to communicate therewith on the opposite side of the center line thereof. Likewise a pipe line 213 leads from the valve 209 around to communicate with the annular passageway within the barrel 170 on one side of the upper center line and a pipe line 214 leads from the valve 209 into the barrel 170 on the other side of the center line. In each barrel, the pipe lines enter the barrel on the respective sides of the stationary abutments 189 and 193. The valves 208 and 209 are preferably operated in unison through a handle 215 with a central shaft 216 interconnecting the shifting members within the valves.

In the position of the various parts as shown in Figs. 1-5, steam is flowing from the pipe 194 through the drum valve slot 200 into the pipe 207 through the valve 209 and the pipe 214 into the barrel 170 to fill the annular passageway between the stationary abutment 189 and the vane 184 thereby pushing the vane on around in a counterclockwise direction, Fig. 2, to carry the rotor 180 therewith. In view of the groove 201, although the drum valve 196 is being rotated as the rotor 180 turns, steam will continue to flow into the pipe 207 through the drum valve until the slot 200 is closed off by the wall between the upper ends of the slot in the valve member 195. While steam is thus flowing into the pipe 207 to force the vane 184 around, an exhaust flow is occurring out the pipe 213 through the valve 209 and into the exhaust line 210.

Since the portion 202 between the ends of the groove 201 is relatively short as above indi-

cated, the drum valve slot 199 will be turned by the drum valve 196 upon a short degree of rotation thereof to permit steam to enter that slot and flow into the pipe 205 through the valve 208 and the pipe 212 into the drum 171 so as to fill the space between the stationary abutment 193 and the vane 190 to tend to force that vane 190 on around also in a counterclockwise direction. The exhaust from the drum 171 ahead of the vane 190 flows through the pipe 211, the valve 208 and into the exhaust line 210. The motor continues to operate then in this particular direction unless the valves 208 and 209 are shifted to their reverse positions.

In the reverse position, for example, the steam flow from the pipe 207 instead of going into the pipe 214 would go into the pipe 213 on the other side of the stationary abutment 189 and the exhaust would come from the pipe 214 through the valve 209 into the pipe 210. Similarly steam in the pipe 205 would flow through the valve 208 into the line 211 and the exhaust would come through the pipe 212 through the valve 208 and into the pipe 210.

The rear plate 174 may carry any suitable power driven mounting means such as the bell housing 217 which encloses in the form herein shown a fly wheel 218 mounted on the outer end of the shaft 176, this mounting being particularly adapted for automotive use. The motor is supported by some means such as the side brackets 219 extending from the plates.

While we have herein shown and described our invention in the best form now known to us, it is obvious that structural variations may be made without departing from the spirit of the invention and we, therefore, do not desire to be limited to that precise form beyond the limitations as may be imposed by the following claims.

We claim:

1. A rotary engine comprising a pair of barrels, plates at the ends of the barrels, a pair of rotors, one revolvably carried in each barrel to have an annular passageway therearound between the end plates, a common shaft to which each of said rotors is fixed, a blade forming an abutment in each barrel, said blade extending transversely across the passageway therein and radially of the rotors, preventing complete flow around the passageway, said abutments being located in a common side of each barrel, a vane carried by each rotor normally extending across the passageway and cooperating with said abutment to divide the passageway into two chambers, the vane of one rotor being angularly displaced in relation to the other vane, and means on the plates for shifting each of said vanes to permit clearance of said abutment upon relative travel of the vanes and abutments one past the other.

2. A rotary engine comprising a pair of barrels, plates at the ends of the barrels, a pair of rotors, one revolvably carried in each barrel to have an annular passageway therearound between the end plates, a common shaft to which each of said rotors is fixed, a blade forming an abutment in each barrel, said blade extending transversely across the passageway therein and radially of the rotors, preventing complete flow around the passageway, said abutments being located in a common side of each barrel, a vane carried by each rotor normally extending across the passageway and cooperating with said abutment to divide the passageway into two chambers, the vane of one rotor being angularly displaced in

relation to the other vane, and means on the plates for shifting each of said vanes to permit clearance of said abutment upon relative travel of the vanes and abutments one past the other, each of said rotors being provided with a slot therethrough, the vane of the rotor being slidably carried through said slot from the interior of the rotor, said vane shifting means comprising a pair of spaced apart arms extending radially inwardly through the rotor slot, and cam track means on the plates engaging the arms interiorally of the rotor.

3. A rotary engine comprising a rotor, a barrel surrounding the rotor plates at the ends of the rotor, said barrel, said plates and said rotor being formed to define an annular chamber therebetween peripherally around the rotor, a fixed abutment across the chamber, a reciprocable vane carried by the rotor and normally extended from the rotor to form a closure across said chamber, and means in the plates withdrawing the vane within the rotor to permit passing by said abutment, said chamber having an intake port on one side of said abutment and an exhaust port on the other side, a rotary valve outside of the barrel having a central partition forming a compartment at each end of the valve, said valve driven at rotor speed by travel of the rotor, and pipes interconnecting the compartment of said valve with a source of steam and said ports, whereby the single valve admits steam in timed sequence, means for reversing the flow of steam in said pipes independently of said rotary valve, and means for manipulating said reversing means.

35 4. A rotary engine comprising a pair of barrels,

plates at the ends of the barrels, a pair of rotors, one revolvably carried in each barrel to have an annular passageway therearound between the end plates, a common shaft to which each of said rotors is fixed, a blade forming an abutment in each barrel, said blade extending transversely across the passageway therein and radially of the rotors, preventing complete flow around the passageway, said abutments being located in a common side of each barrel, a vane carried by each rotor normally extending across the passageway and cooperating with said abutment to divide the passageway into two chambers, the vane of one rotor being angularly displaced in relation to the other vane, and means on the plates for shifting each of said vanes to permit clearance of said abutment upon relative travel of the vanes and abutments one past the other, each of said passageways in the respective barrels having an intake port on one side of its abutment and an exhaust port on the other side, a single rotary valve outside of the barrels having a central partition forming a compartment in each end of the valve, said valve being driven at rotor speed by travel of said shaft, conduits interconnecting said valve with a source of steam, and each of said ports, whereby the single valve admits steam in timed sequence of the travel away from and toward the abutments by the respective vanes, and means exteriorly of the barrels and of the valve for reversing steam flows between the valve and said ports independently of said first rotary valve.

EARL E. BOWERS.

CHARLES M. TUMEY.
